UNITED STATES PATENT OFFICE.

HENRY J. NUTRIZIO, OF NEW YORK, N. Y.

DESIGN FOR A DISPLAY STAND.

Application filed June 14, 1922. Serial No. 2,668. Term of patent 3½ years.

To all whom it may concern:

Be it known that I, HENRY J. NUTRIZIO, a citizen of the United States, residing in the city, county, and State of New York, have invented a new, original, and ornamental Design for Display Stands (Case "A"), of which the following is a specification, reference being had to the accompanying drawings, forming a part thereof, and of which—

I claim:

The ornamental design for a display stand as shown.

HENRY J. NUTRIZIO.
